(57) **CLAIM**

The ornamental design for a tire for automobile as shown and described.

DESCRIPTION

FIG. 1 is a front perspective view of a tire for automobile showing my new design;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof; and,

FIG. 8 is a partial enlarged view of FIG. 2.

The broken lines in the drawings illustrate portions of the tire for automobile that form no part of the claimed design. The dot-dash-dot lines in FIGS. 2 and 8 illustrate the portion of FIG. 2 shown in the partial enlarged view of FIG. 8. The dot-dash-dot lines form no part of the claimed design.
